UNITED STATES PATENT OFFICE

EARL M. BARDEN, OF DETROIT, MICHIGAN, ASSIGNOR TO PACKARD MOTOR CAR COMPANY, OF DETROIT, MICHIGAN, A CORPORATION OF MICHIGAN

PAINTING INSTRUMENT

Application filed July 17, 1930. Serial No. 468,510.

My invention relates to painting instruments and more particularly to guiding means for striping instruments.

In striping a work surface, particularly where a curved ridge of the work surface, such as a window reveal or the like, is utilized as a guiding member, difficulty is experienced in keeping the line at the same distance from the ridge at the curved portion as at the straight portions thereof. The painted line is very likely to be ragged and irregular at the curve. My invention is intended to obviate these difficulties.

An object of my invention is to provide a device for painting certain selected areas of work surface.

Another object of my invention is to provide a device for painting straight and curved lines on a work surface.

Another object of my invention is to provide a striping instrument suitable for use in conjunction with indented portions of a work surface, such as automobile doors and the like, to paint a uniform line at a predetermined distance from the indentation in spite of variations and irregularities in the contour and profile of the work surface.

A still further object of my invention is to provide a means for painting a curved line on a work surface adjacent to both straight and curved portions thereof so that the line shall be symmetrically spaced with respect thereto and so the line itself shall be of the correct width and thickness and clean and sharply defined.

Other objects of my invention will appear in the following description of preferred embodiments taken in connection with the drawings:

Referring to the drawings, Fig. 1 is a view in perspective of my device as it appears while being used to paint a line on a portion of a work surface.

Fig. 2 is a side elevational view of the device shown in Fig. 1;

Fig. 3 is an end elevational view of the device as it appears while in engagement with the work surface;

Fig. 4 is a sectional view of one of the guiding members of my device;

Fig. 5 is a sectional view taken along the line 5—5 of Fig. 2;

Fig. 6 is a bottom plan view of the device showing the various guide members utilized, and

Fig. 7 is a schematic diagram showing the operation of a device constructed according to my invention.

Referring to the drawings and more particularly to Figs. 1 and 2, my device is shown as applied to and utilized for painting a work surface such as the window reveal shown, and comprises an instrument body 10 having a guide roller 11 attached thereto. The body is preferably rectangular in shape and is recessed. (Fig. 5) to provide channels and recesses wherein rotatably mounted gears 12 may be located in order to feed paint to the work surface. These gears are preferably driven by means of the roller 11 which projects to one side of the body. A nozzle 14 is resiliently engaged on the body in such a manner that the nozzle maintains an even pressure against the work whenever it is in contact therewith. Two guide members 15 and 16 are disposed on the side of the body at an angle both with reference to the horizontal and the vertical planes (Fig. 2). The guides are oppositely disposed and are provided with converging spring pressed plungers for a purpose to be hereinafter explained.

The body is mounted upon a shaft 21 which has eccentric engagement by means of the offset 22 with the L-shaped handle 23 which is used for supporting the instrument against the work. A ball bearing 24 is disposed on the handle between it and the offset in order that the instrument may be readily rotatable upon the handle to properly position itself with reference to the work. The handle 23 is engaged to the offset 22 by means of a nut 25 having an extended portion 26 threaded into the offset.

The paint is supplied from a container 31 (Fig. 5) and is fed to the nozzle 14 through channels 32 and 33 radially and longitudinally located in the handle, through the transverse channel 34 in the offset, through the transverse channel 35 in the body, through the chamber in which the co-acting gears 12

of the gear pump are located and through the longitudinal opening 37 in the shaft 38 to and out of the nozzle 14.

Ordinarily, in order to hold a nozzle at the proper distance from a guiding member of the work surface, it is necessary to employ either two guiding members on the instrument spaced at some appreciable distance apart or a large roller of sufficient size to prevent the instrument from "wobbling" with respect to the work. If a single large guide or a plurality of guides are used and the instrument is passed along a curved portion of the ridge of the work, a "wobbling" motion may be impressed on the instrument and transmitted to the work by reason of the irregular engagement of the guide member of the instrument with the ridge in the work surface or other guiding means. If a single guide, large enough to engage the ridge at two spaced points, or two or more spaced guide members are used, the radius of curvature R (Fig. 7) measured from a point equidistant between the two contacting points 25 or guiding members 71 and 72, and on a line 73 joining them, becomes less, as the instrument describes an arc, than the radius of curvature R^1 of the ridge 74 in the work surface, and the nozzle, and line 75 described 30 by the nozzle, are drawn in toward the center of the curvature and nearer to the inner edge of the ridge of the work surface, thereby 35 destroying the symmetry of the line with respect to the ridged portion of the work.

In order to eliminate this difficulty I have provided resilient guiding members, of which there are preferably two in number, in place of one large guiding member or two rigidly mounted, spaced guiding members. These 40 guiding members are preferably comprised of a cylinder 15 (Fig. 4) in which is located a plunger 17 having a rounded outer end and an enlarged inner end which is adapted to constitute a flange upon which a spring 45 43 may be engaged. The end of the cylinder is closed by means of a threaded cap 44 having a portion 45 projecting inwardly from its inner end to constitute a guide for the spring 43. The cap is arranged for longitudinal adjustment within the cylinder in order to provide any desired pressure on the plunger.

The instrument is applied to the work by engaging the roller against the side of the 55 ridge in the work surface and applying the two resilient guide members so that the plungers rest against the bottom of the ridge at the junction of the ridge and the plane of the work surface. The nozzle rests on the ridge or the work surface in accordance with its 60 selected position with reference to the instrument body 10.

When the instrument is held perpendicular to the plane of the work surface, the nozzle 65 is located at the proper position with refer-

ence to the work surface to define a suitable stripe thereon when the instrument is moved along the ridge.

When the instrument encounters a curve in the ridge the spring of the forward guide member is compressed. When the center line of the instrument enters into the curve the nozzle begins to move also in a curve and the following guide member is also compressed so that the pressure of one guide member is balanced against the pressure of the other. This equal pressure of the guiding members permits the roller to accurately space the nozzle with reference to the ridge in the work surface so that the nozzle is at the same distance from the edge of the ridge when the instrument is at a curve as it is when the instrument is at a straight portion of the ridge. The roller, the location of which is indicated by the arrow 76 in Fig. 7, then becomes the sole spacing means and the line 77 defined by the nozzle is properly spaced from the ridge or other guiding member 74.

When the leading guide member reaches a straight portion of the ridge the spring in the cylinder is extended and the plunger continues to engage the ridge in order to constitute a steady means for the instrument. After the center line of the instrument has passed from the curve into the straight portion of the ridge, the following plunger is also extended as it passes out of the curve and the instrument is held with its nozzle at the correct distance from the edge of the ridge.

A painting instrument, made according to my invention, defines symmetrically disposed curves which are spaced at the same distance from the curves of the ridge or other guiding means of the work surface, without irregularities, and also defines straight lines along the straight portions of the work surface guiding means.

The instrument operates quickly and easily and does not need a highly skilled operator to take care of the machine or operate it.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

What I claim is:

1. In combination with a painting instrument adapted for painting a ridged work surface and comprising fluid holding and fluid distributing means, a guide for engaging the ridge in the work surface, and additional guiding means for engaging the ridge portion of the work surface comprising angularly extending spring pressed plungers, said

plungers being arranged one in advance of another behind said guide.

2. In combination with a painting instrument adapted for painting a ridged work surface and comprising fluid holding and fluid distributing means, a guide roller for engaging the ridge in the work surface, and additional guiding means comprising a pair of resiliently mounted guides arranged one in advance of the roller and the other at the rear of the roller.

3. In combination with a painting instrument adapted for painting a ridged work surface and comprising fluid holding and fluid distributing means, a guide roller for engaging the ridge in the work surface and for actuating the fluid distributing means, and additional guiding means comprising a pair of resiliently mounted plungers, disposed on the instrument at an angle with reference to both the horizontal and the vertical planes, for engaging the ridge, one of said plungers being in advance of the roller and the other of said plungers being at the rear of the roller.

25 4. In combination with a painting instrument adapted for painting a ridged work surface comprising fluid holding and fluid distributing means, a roller guide for engaging the ridge of the work surface to partially guide the instrument and a pair of additional resiliently mounted guides spaced in advance of and at the rear of the roller.

35 5. In combination with a painting instrument adapted for painting a ridged work surface comprising fluid holding and fluid distributing means, a roller for engaging the work surface and a pair of guides spaced one on each side of the roller comprising converging spring pressed plungers.

40 6. In an instrument adapted for painting a work surface having a curving ridge portion, a body, a nozzle carried by the body for applying fluid directly upon the work surface, a supporting and guiding roller for the body arranged substantially beside the nozzle, said roller engaging the side of the ridge portion of the surface to guide the body, and a pair of resiliently mounted guides carried by the body, said guides having their bearing ends normally aligning with the roller in the direction of the instrument travel and adapted to engage a side of the ridged portion of the work surface, the bearing ends of said resiliently mounted guides varying in their relation with the roller when operating on a curve to maintain the nozzle outlet uniformly spaced from the guiding ridged surface.

45 7. In a painting instrument, a body having fluid dispensing means associated therewith, a supporting roller for the body, the side of said roller guiding the same, and a pair of spring-pressed guide members carried by the body, said guide members having their bearing surfaces normally in alignment

with the guiding side of the roller in the direction of the movement of the instrument.

8. In combination with an instrument for applying stripes to surfaces having a ridge thereon, a guide roller for engaging the ridge portion of a surface, and a spring pressed guide plunger for engaging the same face of the ridge portion of the surface engaged by the roller, said guide plunger being spaced from the axis of the roller in a direction normal thereto and extending at an oblique angle laterally of the roller.

9. In combination with an instrument for applying paint stripes to surfaces having a ridge thereon, a roller for engaging an edge portion of the ridge of the surface to be striped to partially guide the instrument, and a resilient plunger for engaging the surface at the base of the ridge on the same side engaged by the roller for furnishing additional guide means for the instrument, said plunger being spaced from the axis of the roller in a direction normal thereto.

10. In combination with an instrument for applying stripes to surfaces having a ridge thereon, a guide roller for engaging the ridge portion of a surface to be striped, and a spring pressed guide plunger for engaging the same face of the ridge portion of the surface engaged by the roller, said guide plunger being spaced from the axis of the roller in a direction normal thereto and extending at an oblique angle laterally of the roller and of the roller axis.

In testimony whereof I affix my signature.

EARL M. BARDEN.
